UNITED STATES PATENT OFFICE.

JACOB R. SCOTT, OF NYACK, NEW YORK, ASSIGNOR TO HIMSELF AND
ANDREW H. JACKMAN, OF SAME PLACE.

SEWING-MACHINE.

SPECIFICATION forming part of Letters Patent No. 233,560, dated October 19, 1880.

Application filed March 5, 1880. (Model.)

To all whom it may concern:

Be it known that I, JACOB R. SCOTT, of Nyack, in the county of Rockland and State of New York, have invented a new and useful 5 Improvement in Sewing-Machines, of which the following is a specification.

My improvements relate to machines for sewing boots and shoes wherein the stroke of the needle is automatically varied by the variations in the thickness of the material, so that each stitch shall be drawn tight; and my invention consists, first, in devices operated by the presser-foot to limit the upward stroke of the needle, and, second, in a spring device attached upon the horn for retaining the looper in the proper position relative to the needle.

The needle-bar is hung on a rocking lever that is supported on a vertical standard which rests at its lower end on a beveled slide-block. 20 The slide-block is connected by a crank-lever with the presser-foot, so that the slide-block is moved thereby to raise and lower the needle-carrying standard. The horn is fitted with a piece forming the bed, which piece contains 25 the looper. Upon the horn is a flat spring bearing upon the looper to retain the same in proper position relative to the needle. These features will be more particularly described hereinafter, with reference to the accompanying drawings, wherein—

Figure 1 is a sectional side elevation of a sewing-machine embodying my improvements, and Fig. 2 is a sectional front view.

Similar letters of reference indicate corresponding parts.

A is the standard of the machine, carrying the plates *a a*, which support the mechanism. *b* is the driving-shaft. *c* is a vertical standard fitted in plates *a*, and carrying at its upper 40 end a lever, *d*, that is connected to the arm of an eccentric, *e*, on shaft *b*. *f* is the needle-bar, fitted to slide vertically in plates *a*, and connected by a rod, *g*, with the outer end of lever *d*, and *h* is the presser-bar, fitted to slide vertically in plates *a*, and forced downward by a spiral spring, *h'*.

The standard *c* is fitted at its lower end with a collar, *c'*, having a beveled under side resting on a beveled or wedge-shaped block,

i, which rests on lower plate, *a*, and is slotted 50 for the passage of standard *c*.

Upon a fixed standard is hung a bent lever, *k*, the outer end of which is slotted to receive a pin or stud that projects from a collar, *k'*, on the presser-bar *h*, while the inner end of lever 55 *k* is connected to the block *i* by a pin, *i'*, which is attached to said block, and extends in the direction of the movement of the slide. The pin *i'* passes freely through the lever *k* and is encircled by a spring, *l*, that bears equally on 60 opposite sides of the lever, whereby the lever is held by spring-pressure.

Upon the needle-bar *f* is a stud or projection, *f'*, extending beneath the collar *k'* of bar *h*, for the purpose of lifting the presser-bar *h* 65 at the completion of the upward stroke of the needle. This movement is allowed by the spring *l*, which yields to permit of the movement of lever *k*, the slide *i* being at that moment held in place by pressure of the stand- 70 ard *c*.

It will be seen that by the described construction the position of slide *i* is regulated by the presser-bar, which is raised and lowered according to the thickness of the material beneath it. If the material increases in thickness, the bar *h* is correspondingly raised, and the standard *c* lifted by slide *i* to the same extent, so that as the needle rises it draws the loop tightly, and draws a sufficient amount of 75 thread from the spool to form the loop at the thicker portion; or, if the thickness of the material decreases, the stroke of the needle is shortened by the reverse action, and only so much thread drawn off as is required. 80

B is the horn, fitted at its end with an apertured bed-piece, *m*, that is formed with the tail *m'* and carries the looper *n*. The piece *m* is fitted to turn in the horn *B*, and the tail *m'*, extending within the shoes, acts to retain the 85 piece *m* and looper in the same position relative to the needle as the horn is turned. The looper *n* is fitted to rock on a pivot, as described in my previous application for Letters Patent filed December 19, 1879, and to hold the said 90 looper upward in position for receiving the needle a flat spring, *o*, is attached to the horn *B* and bears upon the under side of the looper. 95

This spring *o* is apertured to receive the rounded under side of the looper, and on the descent of the needle the spring is depressed by the downward-swinging movement of the looper until released by the rise of the needle, when the spring returns the looper to place.

Having thus described my invention, I claim as new and desire to secure by Letters Patent—

- 10 1. In sewing-machines, the combination, with the presser-bar *h*, provided with the collar *k'*, the bent lever *k*, the pin *i'*, the spring *l*,

the slide *i*, and the standard *c*, of the needle-bar *f*, provided with the stud or projection *f'*, substantially as herein shown and described, 15 and for the purpose set forth.

2. In sewing-machines, the combination, with the horn *B*, the revolving bed-piece *m*, and rocking looper *n*, of the spring *o*, substantially as and for the purpose set forth.

JACOB R. SCOTT.
